UNITED STATES PATENT OFFICE.

FRANK KUSTERLE, OF KENOSHA, WISCONSIN, ASSIGNOR TO SIMMONS COMPANY, OF KENOSHA, WISCONSIN, A CORPORATION OF DELAWARE.

BED-SPRING CORNER.

1,359,714.

Specification of Letters Patent. Patented Nov. 23, 1920.

Application filed April 12, 1918. Serial No. 228,183.

To all whom it may concern:

Be it known that I, FRANK KUSTERLE, a citizen of the United States, residing at Kenosha, in the county of Kenosha and State of Wisconsin, have invented certain new and useful Improvements in Bed-Spring Corners, of which the following is a specification.

My invention relates to improvements in bed spring corners and is of particular service when used in connection with bed springs in which the bed bottom comprises a wire link or other flexible fabric.

The principal objects of the invention are to provide a corner connection between the side members and the cross members or end members of the spring frame, the arrangement being such that the resiliency of the bed bottom fabric will serve to maintain the various parts in position; to provide a corner of the class described which may be constructed of relatively cheap material which might otherwise go to waste in case it were not so utilized; to provide a corner of the class described in which the corners may be made accurately to size and may be assembled together rapidly and efficiently; to provide a corner of the class described which may be constructed of metal not liable to break when subjected to shocks or sudden stresses; to provide a corner of the class described which shall be neat, simple and practical in design and inexpensive to manufacture, and in general to provide an improved corner of the character referred to.

In the drawings which illustrate a preferred embodiment of my invention, Figure 1 is a side elevation of the corner as used on a spring frame equipped with a wire link fabric;

Fig. 2 is a section taken on the line 2—2 of Fig. 1;

Fig. 3 is a section taken on the line 3—3 of Fig. 1, and

Fig. 4 is a section taken on the line 4—4 of Fig. 1.

Referring to the drawings, 10 represents a customary angle iron side rail which is used to connect and embrace together the foot and head ends of a metal bedstead. Such side or supporting rail 10 constitutes the support for the bed spring which, in the present instance, comprises a wire link fabric

11 connected to the spring frame by means of helicals 12. The principal members of the spring frame are a pair of side members which, in the present instance, take the form of heavy steel tubes 13. It will be observed that the said side members 13 are depressed below the surface of the wire fabric 11 so as to permit the latter to sag without touching the side member 13 when the bed is occupied.

The outer ends of the helicals 12 are hooked into apertures spaced apart along the top flange, or leg, of the angle iron 14 which constitutes one of the cross pieces or end members of the spring frame. 15 designates as a whole my improved corner, the function of which is to connect together the cross piece 14 and the side member 13, while at the same time serving as a bracket by which the spring frame is supported upon the side rail 10.

My improved corner 15 is composed of two parts, one of which is a length of angle iron or other flanged metal folded or bent to provide a loop 16 in which is located the end of the side member 13. It will be observed that the sides 17 and 18 of the corner are bent up parallel as shown, the flanges 19 and 20 substantially abutting against each other as shown at 21 and being cut away at their lower ends to fit against the rounded upper surface of the side tube 13. The cross plate 21 is riveted as indicated at 22 to the abutting flanges 19 and 20 and thus maintains the parts 17 and 18 of the corner in fixed and parallel relation. The portion of said cross plate below the rivets 22 is also cut away or conformed to fit the upper side of the tube 13; while the outer end of the said cross plate 19 is extended a sufficient distance to overhang the side rail 10 of the bedstead. In order to prevent relative movement of the spring frame and the side rail 10, I prefer to provide a small downward projection 23 on the end of the cross plate, thus preventing lateral movement of the corner.

The angle iron cross piece 14 is secured to the corner 15 by means of a pair of spaced apart vertically extending slots 24 which receive a pair of similarly spaced lugs 25 on the upright parts 17 and 18 of the corner. It will be observed that the tension of the spring 12 serves to maintain the angle iron

14 in engagement with the said lugs 25, while angular movement of the corner in a vertical and longitudinal plane is prevented by reason of the extreme end of the tube 13 engaging the interior of the loop 16, the upper surface of the tube 13 being engaged also by the cross plate 21^a and the cut away lower ends of the flanges 19 and 20.

Rotation of the corner upon and around 10 the axis of the side tube 13, is prevented by means of a pin 26 riveted to the loop 16 as shown at 27, said pin 26 fitting within the open ended slot 28 cut into the end of the cross tube 13. Said pin 26 also prevents the 15 corner from sliding along the tube.

The scope of the invention should be determined by reference to the appended 20 claims, in view of the fact that the described details of mechanical construction may be modified to suit individual requirements 25 without sacrificing the benefits of the invention.

I claim—

1. In a device of the class described, the combination with a longitudinal side member of a riser mounted on the end thereof and comprising an angle iron, L shaped in cross-section, and having an intermediate portion of one of the flanges cut away and 25 the other flange bent intermediately around the under side of the longitudinal member and extending upwardly thereabove at each side thereof, so that the remaining portions of the first mentioned flange engage the top 30 of the side member at a distance from the end of said side member, to coöperate with the bent portion of the other flange to clamp the end of the longitudinal member therebetween.
- 40 2. In a structure of the class described, the combination with a longitudinal side member of a plate bent intermediate of its ends to afford a riser engaging under the end of the longitudinal member, and having spaced upright legs at each side thereof 45 extending thereabove, and a transverse connector secured at the inner ends of the upright legs to hold said legs in separated relation and engaging over the longitudinal member at a distance from the end to clamp 50 the end of the longitudinal member between the transverse connector and the looped portion of the plate underlying the end of the longitudinal member, said transverse connector being extended laterally to engage a support at the side of the longitudinal member.
- 55 3. In combination, a tubular side member, an angle iron cross piece and means connecting said parts comprising a length of strip metal folded to fit and include the end of said tubular side member, the said strip having its ends flanged, the flanges abutting against each other when the strip is folded,

- 60 65 means preventing separation of the said

folded ends, and a part on said folded member interlocked with and extending into said cross piece.

4. In combination, a supporting rail, a tubular side frame member, an angle iron 70 cross piece having a vertical leg provided with an aperture, a length of strip metal centrally folded to include and fit the end of the said tube, its ends being upturned and substantially parallel and provided with opposed flanges and lying substantially in the same vertical plane, one of said ends having a lug entering the aperture in said angle iron for maintaining the latter in fixed relation, a bed fabric resiliently connected to the 80 horizontal leg of said angle iron remote from said lug whereby the angle iron is maintained in engagement with said lug, and a cross plate united to both of said flanges and having an outer extension resting upon the said rail.

5. In combination, a supporting rail, a tubular side frame member, an angle iron cross piece having a vertical leg provided with an aperture, a length of strip metal 90 centrally folded to include and fit the end of the said tube, its ends being upturned and substantially parallel and provided with opposed flanges substantially abutting 95 against each other, a lug on one of said parallel ends entering the aperture in said angle iron for maintaining the latter in fixed relation, a bed fabric resiliently connected to the horizontal leg of said angle iron remote from said lug whereby the angle iron 100 is maintained in engagement with said lug, a cross plate united to both of said flanges and having an outer extension resting upon the said rail and means for preventing movement of said strip on the end of said 105 side member.

6. In combination, a supporting rail, a tubular side frame member, an angle iron cross piece having a vertical leg provided with an aperture, a length of strip metal 110 centrally folded to include and fit the end of the said tube, its ends being upturned and substantially parallel and provided with opposed flanges substantially abutting against each other, a lug on one of said parallel 115 ends entering the aperture in said angle iron for maintaining the latter in fixed relation, a bed fabric resiliently connected to the horizontal leg of said angle iron remote from said lug whereby the angle iron is 120 maintained in engagement with said lug, a cross plate united to both of said flanges and having an outer extension resting upon said rail, and means for preventing movement of said strip on the end of said side 125 member, the arrangement including means on said folded strip engaging the upper surface of the tube at a point spaced apart from the end of said tube.

7. In a bed, the combination with a side 130

5 rail and a longitudinal bed bottom member, of a riser on the end of said member comprising an angle iron, L shaped in cross section, having one flange thereof cut away intermediate of the ends, and the other flange bent intermediately to embrace the under-side of the longitudinal member, and having the remaining portions of the first men-

tioned flange extended over the longitudinal member, and a transverse member secured 10 to said remaining flange portions at laterally spaced points and projecting laterally from the riser over the rail so as to be supported by said rail.

FRANK KUSTERLE.
